UNITED STATES PATENT OFFICE

ALFRED ALSAKER, OF CHICAGO, ILLINOIS, ASSIGNOR TO THE DELTA-STAR ELECTRIC COMPANY, OF CHICAGO, ILLINOIS, A CORPORATION OF ILLINOIS

BUS CLAMP

Application filed April 29, 1927. Serial No. 187,671.

My invention relates to a novel method of and means for producing a joint in copper conductors of the bar type. It is the practice to make buses and like heavy current carrying parts of flat copper bars of rectangular section because of the ease of working and because of superior cooling ability. In joining such bars to each other or to other bars the accepted practical method is to 10 clamp them mechanically, as by bolts and clamping plates. For mechanical rigidity and chiefly for electrical conductivity, it is desirable that the faces of the parts to be joined be uniformly in contact under a relatively high pressure.

I have found that the unit pressure required to make a satisfactory joint is dependent upon the current to be carried, that is, upon current density of the joint.

Prior to this invention flat clamping plates have been used. These plates overlap or overhang the edges of the parts to be joined and both draw these overhanging edges together. The plates of the prior art are provided with flat faces, and when it is attempted to draw the plates tight against the bars, the plates spring under the pressure and the edges of the plate bite into the metal of the bar. While a total pressure is thus secured of as high a value as may be desired, the distribution of the pressure is not proper and the joint does not have the desired conductivity and it tends to overheat.

According to the present invention the clamping plates are so constructed as to give a uniform pressure over their faces when drawn tight. I take advantage of the elasticity of the plates by making the face of the clamp convex and the degree of convexity, together with the character of the material employed, and the area of contact to be secured are so inter-related and coordinated that when the clamp is drawn tight the plate is sprung or pressed to bring the convex flat face substantially into a plane. This automatically provides the proper clamping pressure. The clamps are not pressed beyond the elastic limit and hence when pressure upon them is released they assume the original

spherical or convex shape on the working face.

Now in order to acquaint those skilled in the art with the manner of constructing and operating a device according to my invention, I shall describe in connection with the accompanying drawings a specific embodiment of the same.

In the drawings,—

Figures 1, 2 and 3 are diagrams explaining the types of joints which are commonly met with in the practice of joining bars;

Figure 4 is a front elevational view of a clamping plate embodying my invention;

Figure 5 is an end elevational view looking at the right end of Figure 4;

Figures 6, 7 and 8 are sections taken on the lines 6—6, 7—7, and 8—8 of Figure 4, respectively;

Figure 9 is a face view of a straight or two bolt clamp;

Figure 10 is a rear elevation of the same;

Figure 11 is a longitudinal vertical section taken on the line 11—11 of Figure 9;

Figure 12 is a transverse section taken on 75 the line 12—12 of Figure 10;

Figure 13 is a rear view of a modified form of four bolt clamp;

Figure 14 is a left end elevational view of Figure 13;

Figures 15 and 16 are sections taken, respectively, on the lines 15—15 and 16—16, of Figure 13;

Figure 17 is a face view of a modified two bolt clamp of my invention;

Figure 18 is a rear view of another modified form of two bolt clamp;

Figure 19 is a right side elevational view of Figure 18 taken on the line 19—19 showing the lower part of the same in section;

Figure 20 is a longitudinal vertical section of the clamp shown in Figure 18;

Figure 21 is a transverse section on the line 21—21 of Figure 18; and

Figure 22 is a cross section taken on the line 22—22 of Figure 18 or Figure 20.

The general features of this clamp are disclosed in my co-pending application, Serial No. 137,928, filed September 27, 1926, which 100

has issued as Patent 1,831,798 on Nov. 17, 1931.

Whereas the clamps, which I shall herein describe, are made of cast metal, preferably 5 bronze, in order to secure high mechanical strength, relatively good electrical conductivity, and low cost of manufacture, it is to be understood that the clamps may be made of sheet metal suitably stamped in a forming 10 die, or dies.

It is to be observed fundamentally that these clamps are literally loading springs. While they appear to be rigid cast metal they are, as a matter of fact, springs of great 15 stiffness and small flexure or throw. Also, whereas I describe herein a convex or spherical clamping or engaging face, it is not essential that the convexity of the face be strictly spherical, and I consider as coming 20 within my invention any clamping plate the clamping surface of which is convex whether or not the convex surface is spherical or of specifically different curvature.

The amount of current which flows 25 through a joint where the clamp is used in making a joint determines in some degree the pressure which must be applied between the bars to be joined.

Most joints in bus bars are made in straight 30 runs, that is, 180° joints, or in taps, that is, 90° joints.

In Figures 1, 2 and 3 I have illustrated typical joints which are to be made. Assume that the longitudinal bar 1 is to be joined to 35 the vertical tap 2 and that the area of the joint is, therefore, the width A of the bar 1 in one dimension, and the width B of the bar 2 in the other dimension. Assume that in this case the two bars are of equal width, that 40 is, A equals B. Such a joint is made where the same current which flows through the bar 1 may flow through the bar 2 and as a result the entire flow of current must pass through the joint.

45 In case 2, Figure 2, the main run of bus is shown in the horizontal bar 3 and the tap is taken off as bar 4 which in this instance is of half of the width of the bar 3. In this case A equals 2—B. This joint is designed so that 50 the current flowing in the bar 3 only a portion, in this case one-half, is to be taken off in the tap 4.

In the case illustrated in Figure 3, the longitudinal run of bus bar 5 is connected to a 55 vertical tap 6 and the vertical tap is designed to take current from both directions, or vice versa, to deliver current in both directions with respect to the bar 5. In this case it will be seen that the superficial area of the joint 60 may be the same in Figures 2 and 3, but the current density in Figure 3 is twice the current density in Figure 1. The current density of the joint in Figure 2 is the same as that in Figure 1.

65 The proper pressure has been found by ex-

periment to be in the case of Figure 1 about 200 lbs. per square inch. This provides the proper conductivity of the joint. The same degree of pressure is not required in Figure 2, since the bar B may more easily be bent to 70 or forced into conformity with the surface of the bar 3 and less actual pressure per unit area is required to make a satisfactory joint. However, in the case of Figure 3, it is seen that the current density is doubled over that 75 shown in Figure 2, even though mechanically the same superficial area and dimensions of the joint occur.

The present line of clamps has, therefore, been designed with a convex face and of suitable strength so that when the clamping plate or clamp is flattened down against the bar, the correct pressure is obtained, and this correct pressure in terms of unit pressure of pounds per square inch is reckoned according to the 80 following equation:

$$\text{Unit pressure} = \frac{200 B}{A}$$

In the above equation B represents the tap 90 and A represents the run of bus in inches of width.

In Figure 4 I have illustrated a clamping plate such as is suitable for clamping together 95 the bars 1 and 2 in Figure 1.

This structure comprises an open rectangular frame member having the sides thereof formed of bars 7, 8, 9, 10 with integral bolting lugs 11 at the corners thereof, and with cross intersecting bars 12, 12 lying within the open frame. The section of the side bar 10 is shown in Figure 6 as comprising an L-shape consisting of a relatively narrow vertical flange 13 and a horizontal flange 14, the lower surface of which at 15 partakes of the convexity with which the engaging or contacting face of the clamp is constructed. In Figure 5 the convexity of the contacting face 16 is indicated by the dotted line 17, which dotted line indicates a plane between 110 the corners of the active face of the clamp. This plane 17 indicates theoretically the position into which the convex face is forced when the clamp is under full clamping pressure. As a matter of fact, the bars themselves 115 are also sufficiently elastic to have considerable give with the result that the convexity of the plate does not altogether disappear, but the proper clamping pressure of the plate with respect to the bars to be joined is indicated when the edges of the plate are tight against the edges of the bar, so that a feeler, that is, a thin metal strip used for test purposes can no longer be forced between the edges of the clamp and the bars to be joined. 120

The cross bars in section are T-shaped comprising a vertical flange 18 and a horizontal flange 19, the lower surface of which is convex as indicated at 20.

In the embodiment of Figure 13 a different 130

form of square clamp is illustrated. The general outline of the clamp is the same. It comprises the open rectangular frame having the side members 21 which are of a section, as shown in Figure 16. It also includes the cross diagonal bars 22 which are of an inverted U-shape section as shown in Figure 15. The bearing faces 23 and 24, respectively, of the bars 21 and 22, are convex as explained in connection with the previous embodiment. Integral bolting lugs 11, 11 are provided at the corners for applying pressure to the bars to be clamped. It is to be noted in this modification that the metal is used to slightly better advantage so that for a given weight of material it secures relatively greater rigidity and hence greater pressure. The clamp shown in Figure 4 is a heavy duty clamp and, as will be seen by comparing the radius of curvature, the clamp of Figure 4 is intended to apply greater pressure to the bars to be clamped than is the plate of Figure 13.

The curvature on the contact face of the clamp is secured by grinding the same on a concave grinding wheel. The radius of curvature varies from 25 feet to 35 feet, depending upon the area of the clamp and other factors. These other factors include the elasticity of the metal, that is, Young's modulus, the dimensions of the clamp section, the number of bolts used to secure the clamping effect, and the areas to be clamped. The dimensions of the clamp section are designed to withstand the total deflection at full pressure without exceeding the elastic limits of the material employed. These clamps may be made of bronze and of malleable iron. Other materials may be used if desired.

Instead of using a four bolt rectangular clamp a three bolt triangular clamp may be employed. The principles upon which the same are constructed and the mode of operation are the same as above described.

Where it is desired to clamp a number of bars together with spacers between them to prevent vibration, and the like, a two bolt clamp may be employed. In the device of Figure 9 the body of the clamp is relatively narrow and has the bolting lugs 11, 11 at the ends with the intermediate sections in the form of an inverted U, as shown in Figure 12. The two legs 26, 26 are convex at their lower ends as indicated at 27 and at their upper ends are joined by the web 28 which extends the full length of the clamp.

In Figures 17, 19, and 21 I have indicated a heavy duty clamp such as may be employed for wider bars or for greater pressure, this bar consisting of the bolting lugs 11 at the ends and an intermediate section which comprises a central web 29 with the raised flanges 30, 30 on the outside thereof, extending flanges 31 wider at the center than at the ends with the ribs 32 on the engaging or clamping face, which ribs which are ground

to the convex form desired. The tension flanges 30, 30 are thus placed substantially mid-way between the compression ribs 32, 32 to get an even distribution of pressure.

In Figures 18, 20 and 22, I have shown a heavy duty clamp similar to the clamp shown in Figure 9, which includes the bolting lugs 11, 11 at the center and a lozenge shaped body comprising three webs 33 joined by the plate 34. The webs 33 are convex at their free edges 35 to bear upon the bars to be clamped.

In the joint shown in Figure 1, a clamp such as shown in Figure 4 or 13 is employed, the bolting lugs 11 falling outside the edges of the bars to be clamped with whatever working clearance is required. For making the joint shown in Figure 2 either a triangular clamp or oblong rectangular clamp may be employed, and for Figure 3 an oblong rectangular clamp is preferably employed.

While I have described the clamp of my invention as employed primarily for making joints between bars, it is to be understood that these clamps may be employed merely for holding bars together or for holding bars upon supports, as on insulators and the like.

It will be seen that the clamp of my invention is highly advantageous in that the pressure is first applied centrally and then is distributed outwardly from the center by the springing of the plate. The clamp serves as an automatic indicator of the right pressure, since the inherent design of the plate employed in each particular case is such that when the convex face has been deflected to a point where the entire surface of the same is in engagement with the flat bar, the proper pressure has thereby been secured and further tightening of the bolt is not required.

In the specific forms which I have illustrated and described the engaging face is convex and the opposite side flat. The plate may be concave on the back or otherwise formed. While I have shown an open frame or skeletonized plate, and while I find the same advantageous, it is not essential. It is found that thin metal sections and an open frame give greater strength for a given weight of metal.

By the term "double convexity" as used in the claims I mean a surface convex in all directions, that is, a surface so convex that a tangent plane touches the same at one point only rather than along a line.

I do not intend to be limited to the precise details shown or described.

I claim:

1. A spring clamping plate for clamping bus bars comprising an elastic convex metal plate of double convexity, requiring a relatively large force below the elastic stress limit of the metal to deflect the same into contact with a flat surface with which the same engages.

2. A clamping plate for bus bars and the

like comprising a resilient cast metal plate having a convex face for engaging the bus bar, and lugs along the margins of said plate for pressing the plate against the bus bar until the convex face is substantially flattened, the portion of the plate between any lug and its adjacent lugs being convex when the plate is unclamped.

3. A clamping plate for clamping bus bars
10 and the like comprising a metal plate substantially flat on one side and substantially spherical on the other side, and of a radius of curvature such as to permit deflection of the spherical side to a substantially flat surface by a force below the elastic stress limit of the metal.

4. In combination with a pair of bus bars, means including a spring clamping plate for clamping the bus bars, said clamping plate
20 comprising an elastic convex plate of double convexity, the convex face thereof being deflected by a relatively great force into planar contact with the surface with which it engages, the metal of the plate being stressed
25 below its elastic limit by the deflection, and the force deflecting the plate exerting the clamping pressure between the bus bars.

In witness whereof, I hereunto subscribe
my name this 27th day of April, 1927.
30 ALFRED ALSAKER.
